UNITED STATES PATENT OFFICE.

MARQUIS T. PEW, OF PARKER'S LANDING, PENNSYLVANIA.

VALVE-CUP.

SPECIFICATION forming part of Letters Patent No. 645,004, dated March 6, 1900.

Application filed March 1, 1899. Serial No. 707,306. (No model.)

To all whom it may concern:

Be it known that I, MARQUIS T. PEW, a citizen of the United States, residing at Parker's Landing, in the county of Armstrong and State of Pennsylvania, have invented a new and useful Rope Valve-Cup, of which the following is a specification.

My invention relates to valve-cups for packing for pump mechanisms, and particularly for those pumps designed for use in deep wells in pumping oil, salt water, &c.; and the object in view is to provide a simple, strong, and durable packing ring or cup adapted to withstand rough usage to which devices of this class are exposed and to resist the effect of the liquids, the same being of a sufficiently-yielding quality to form an efficient contact with the inner surface of the working barrel of the pump and at the same time sufficient strength to resist the crushing effect of the liquids.

Further objects and advantages of this invention will appear in the following description, and the novel features thereof will be particularly pointed out in the appended claim.

In the drawings, Figure 1 is a side view of a portion of an oil-well-pump piston provided with packing-rings constructed in accordance with my invention. Fig. 2 is a detail view in perspective of the improved packing cup or ring. Fig. 3 is a central sectional view of the same. Fig. 4 is a detail view showing the cord or fibrous wrapping partly unwrapped to expose the lining, of canvas.

Similar reference characters indicate corresponding parts in all the figures of the drawings.

In the preferred embodiment of my invention the packing ring or cup consists of a body portion of fibrous wrapping 1, such as hemp or cotton cord, provided with inner and outer coatings 2 and 3, of rubber cement or dental rubber, while within the body portion 45 is a lining 4, of canvas or similar material, preferably consisting of one or more wraps held in place by the inner coating of cement. In the construction of the ring the lining is first applied to a mandrel in the form of a

strip of canvas, with the warp running parallel with the axis of the mandrel, and hence parallel with the axis of the ring or cup when finished. One or more wraps of the canvas strip may be made about the mandrel, after which the inner layer or coating of cement is applied. Secondly, the cord or other material which is to form the fibrous wrapping is coiled around the mandrel upon the lining, the coil starting from the bottom of the cup and progressing toward the upper edge thereof. Subsequently the outer coating of cement is applied. The device is subjected to heavy pressure by any suitable means forming no part of my present invention to cause the cement to entirely fill all of the interstices both 65 interiorly and exteriorly of the fibrous wrapping and including those between the wraps or coils, and, finally, the device is subjected to a vulcanizing operation. The flange or lip 5 at the bottom of the cup and surrounding 70 the central opening therein is formed at the time of subjecting the device to pressure, as above mentioned, and in order to strengthen and stiffen this flange or rim a metallic ring 6 may be embedded therein.

From the foregoing description it will be seen that with the exception of the stiffening-ring which is employed in connection with the rim or flange at the bottom of the cup the entire device is composed of flexible material and that while the warp of the lining extends vertical or parallel with the direction of movement of the packing-ring when in use the fibrous wrapping which forms the body of the ring extends spirally. Thus the lining serves to counteract any tendency of the coils of cord or other wrapping to separate, while the absorbent quality of the cord provides for expansion of the ring, and hence an effective contact of the exterior surface 90 thereof with the wall of the pump-barrel; also, it is obvious that the upper edge of the cup or ring is sufficiently flexible or yielding to allow a snug fitting thereof in the pump-barrel.

Various changes in the form, proportion, size, and minor details of construction within the scope of the appended claims may be re-

sorted to without departing from the spirit or sacrificing any of the advantages of the invention.

Having described my invention, what I claim is—

A packing-cup or analogous device shaped to provide a flaring wall inturned at its reduced end around an opening therethrough, and having the body portion partly composed 10 of a fibrous wrapping located mainly near the enlarged terminal and provided with an outer coating of rubber substance and a lin-

ing of textile fabric, the fibrous wrapping being spirally disposed, and the outer portion of the inturned part of the wall having a metallic ring embedded therein. 15

In testimony that I claim the foregoing as my own I have hereto affixed my signature in the presence of two witnesses.

MARQUIS T. PEW.
